DESIGN FOR A DRESS ENSEMBLE

Josephine Schwartz, New York, N. Y.

Application February 26, 1938, Serial No. 75,419

Term of patent 3½ years

To all whom it may concern:

Be it known that I, Josephine Schwartz, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a rear view of the dress unit shown in Figure 2.

Figure 4 is a rear view of the jacket unit of the dress ensemble shown in Figure 1.

The characteristic feature of my design resides in the combination on the ensemble disclosed, of the contrastingly colored braid trimmed net jacket portion, in association with the braid trimmed dress, as shown.

I claim:

The ornamental design for a dress ensemble, substantially as shown and described.

JOSEPHINE SCHWARTZ.
